UNITED STATES PATENT OFFICE.

JAMES J. O'REGAN, OF WOODHAVEN, NEW YORK.

TYPE-WRITING MACHINE.

1,141,651.

Specification of Letters Patent.

Patented June 1, 1915.

Application filed September 3, 1914. Serial No. 859,953.

To all whom it may concern:

Be it known that I, JAMES J. O'REGAN, a citizen of the United States, and a resident of Woodhaven, county of Queens, Long Island, New York, have invented certain new and useful Improvements in Type-Writing Machines, of which the following is a specification.

My invention relates to typewriting machines, and particularly to that class of typewriting machines, the writing of which may be read by blind persons.

The writing done by my machines consists of projections embossed in the paper and arranged in groups. The projections of each group have a certain arrangement to represent different letters, according to the "Braille" or other similar systems of writing. The projections are embossed in the paper by forcing the paper into depressions in the platen or die plate on the paper carrier of the machine by means of pins operated by the keys of the machine.

One object of my invention is to provide a simplified form of frame work for supporting the keys and the carriage by stamping a base, having key supports and guides, and a carrier bed, or support out of sheet metal, and securing these parts together in a simple way.

A further object is to provide a simple form of carriage and escapement mechanism carried thereby and to mount the carriage and its support in a simplified way.

A further object is to provide a die plate by providing one of the longitudinal bars of the carriage with groups of depressions arranged throughout the length of the bar, said bar passing across the ends of depression making bars, as the carriage moves under the action of a spring when released by the escapement.

Although the disclosure of my invention herein shows its embodiment in a specific form of mechanism, I do not, however, wish to limit myself to this particular form, as I do not wish to be limited to the projection making bars coöperating with the recessed platen, but may extend my invention to embody any means for recording a depression in the key upon paper.

My invention further consists in the combination and arrangement of parts, and in the features of certain of said parts, as will hereinafter with more particularity appear

from the detailed description and accompanying drawings, in which—

Figure 1 represents a top view,—of one form of device embodying my invention,—Fig. 2 represents a cross section of the same device:—Fig. 3 represents a top view of my device with the carriage removed and portions of the table broken away to more clearly show the mounting of the keys; Fig. 4 represents a front view with portions broken away: Fig. 5 is a view of the carriage from the under side, with parts broken away: Fig. 6 is a view similar to Fig. 3, with the keys removed: Fig. 7 is a front view of the base and table: Fig. 8 is a section 8—8 of Fig. 6, Fig. 9 is an end view of the base and table, and Fig. 10 is an enlarged detail view.

The herein described embodiment of my invention has a frame comprising a base 1, a carriage bed 10 and a carriage 30 all of sheet metal. There are two openings stamped out of this base, so that the base comprises the side bars 3 and the end bars 4, and a center bar 5. Attached to the end bars 4 are the flanges 2, which are bent upwardly. Attached to the center bar 5 are the flanges 6 for supporting the keys, and a flange 7 for supporting the escapement mechanism. Attached to two of the side bars are the upstanding flanges 7', having the openings 7" for guiding the operating keys. In the flanges 2 there are openings 8. The carriage bed 10 comprises a table top 11 and downwardly extending end portions 12. Attached to the end portions 12 are lugs 13, which may be inserted within the openings 8, by spreading the end portions 12 apart. The resilience of the said end portions 12 thereupon holds said projections within said opening 8. As a further precaution, the ends of these projections may be bent down flat upon the flanges 2. These projections 13 are made in the operation of stamping out the carriage bed 10, as clearly appears from Figs. 6 to 9. In the top of carriage bed 10 and ends 12, there is cut an opening 14, and the opening 15. These openings extend throughout the length of the top of the table.

The carriage 30 comprises a flat base portion and two upwardly extending end portions 31. In these end portions are mounted the two rubber covered rollers 32. These rollers comprise the shafts 33 and the cover 34.

ing 34. The shafts are resilient and this resilience, with the resilience of the rubber, tends to securely hold the paper upon which the impressions are to be made. The flat base of the carriage comprises three longitudinally extending bars, 35, 36 and 37. The bar 36 has one edge turned down to form a flange 38 and this flange extends into the slot 15 in the top of the table, serving to 10 guide the carriage in its forward and backward movements. At the ends of the bars 35 and 36, small lugs 39 are left when the carriage is stamped out. The lugs 39 on the bar 36 are cut out of the flange 38 and extend 15 down into the slot 15 and are bent under the table top. In the ends 12 of the table, just below the top 11 thereof, are the slots 40 and 41, which open into the slots 14 and 15 respectively. When the carriage is slid onto 20 the table from the end the lugs 39 pass freely through slots 40 and 41. At the middle of the carriage there are lugs 42 and 43, similar to the lugs 39, only they are longer and will not pass through the openings 40 and 25 41. When the carriage is first slid onto the table, these lugs are left in their normal position, that is, in the same plane as the base of the carriage,—that is, in the same plane as the bars 35 and 36 respectively. When 30 the carriage has been slid on far enough to bring these lugs within the ends 12 of the table, these lugs are bent underneath the edge of the table top 11, and assist in holding the carriage down to the table top and 35 when they strike either of the ends 12 of the table, they limit the movement of the carriage. Pivoted to the flange 7 is the plate 44, to which is secured a yielding member 45; pivoted to the ends of the carriage is an 40 escapement rack 46, which comprises a bar bent to comprise two parts at right angles. The pivots for this bar are at the extremity of one of the parts, and on the edge of the other of the parts are formed the teeth 49, 45 which are spaced apart a distance to allow the carriage to move the proper amount, as will hereinafter appear. Formed integral with this bar, there is the upstanding lever 47 which, when pressed backwardly, swings 50 the bar around its pivot. The yielding member 45 normally engages one of the teeth of the rack and is held against the plate 44 by the pressure of the carriage, caused by the carriage actuating mechanism hereinafter 55 described. Attached to the plate 44 is a space key 48. When this key is pressed, the plate is oscillated so that the yielding member 45 is swung out of engagement with a tooth of the rack, so that the plate 44 engages said tooth. The resilience of the yielding member causes it to spring away from the plate 44, and when the key 48 is released, the member 45 engages the next succeeding tooth and the plate 44 is swung out of engagement when the tooth, which it had

been in engagement with, and the carriage is permitted to move forward under the force of its actuating mechanism, until the member 45 contacts the member 44. It is thus seen by oscillation of the member 44, 70 a step by step release is afforded. When the lever 47 is pressed backward, the part of the bar 46, which carries the teeth 49 is swung forward and the teeth 49 are swung out of alinement with the member 45, and the carriage may be freely moved in either direction. The carriage may be returned to its normal position without swinging the escapement bar, because the pressures of the teeth 49 on the yielding member 45 will 75 cause said member to yield, permitting the teeth to slide over it. The operating keys comprise flat bars 50, which pass through the openings 77, in the guide member 77, and are journaled on the bolt 51, which is held in the flanges 6, and journaled on the bolt 51, between the keys, are the spacing collars 52. Joined to the ends of the keys 50 are the impression bars 53, which extend upwardly and through openings 54 in the 80 table top 11. Attached to the under side of the table top 11 is a reinforcing and guiding block 55, having openings 56 which register with the openings 54. Surrounding the bars 53 are springs 53' for holding the 85 keys 50 in position when the yoke 70 is depressed by any other key. In the lower face of the bar 37 of the carriage, there are formed depressions 57 which are generally conical, but which have rounded edges, so that an impression will be made by the rounded or conical ends 58 of the bars 53, even though the depressions 57 are not exactly in register with the openings 54. The bar 37 is pressed upwardly relative 90 to the ends of the carriage when the carriage is stamped out, in order that a space may be provided between the bar 37 and the table top for the paper P to pass through freely. The inner edge of this bar 37 is 95 bent upwardly at an angle to the table top to form a flange 59, so that between said flange 59 and the table top there is a guide for the paper as it leaves the rolls 32. Secured to the bar 35 of the carriage is a flat 100 spring 60, which presses down one face of the escapement bar 46, holding it in position, and extending outwardly from the upper part of the bar 46 is a lug 61 integral therewith, which rests upon the bar 35, and prevents the escapement bar from being swung out of alinement with the member 45 by the spring 60. A part of the metal which is cut out of one of the ends 12 to form the slot 14 in the table is bent around into two 105 arms, 62 and 63. These arms are perforated at 64 and inserted therein is a bar 65 to which is attached the inner end of a spiral spring 65', the other end of the spiral spring being attached to the end of the carriage 110

farthest from this spring mount at 66. The bar 65 is rotated to increase the tension of the spring and a pin 67 is inserted through the hole in the bar and an opening in an ear 38 on the arm 63. Pivoted to the sides 12 of the table, at 69 is a universal bar in the form of a yoke 70 which extends forward and passes under all of the operating keys 50. An opening 71 in this yoke accommodates the key 48, and the spring 72 presses the yoke upward, so that upon every depression of a key 50, the escapement key is operated and the keys 50 are held at the top of the guide openings 77.

15 In the description and claims, wherever the term "carriage bed" is used, it is intended to define broadly a supporting means for the carriage and is not intended to be limited to the U shaped member embodied 20 in the device described. In the description the member carrying the depressions 57 has been designated the bar 37. This member is in reality the platen, and will be referred to in the claims as such. It has groups of 6 25 depressions, one for each key, said groups being spaced apart a distance equal to the distance between the teeth of the escapement rack.

In the operation of the device, the paper 30 P is inserted between the rolls 32 under the flange 59 and between the platen bar 37 and the table top. The characters are made by depressions of different combinations of the 6 keys 50 and the escapement permits the 35 carriage to move along the proper distance between each character.

What I claim as my invention and desire to secure by Letters Patent of the United States is the following:—

40 1. In a typewriter, a frame comprising a base and a carriage bed fixed thereto, a carriage supported on said bed for reciprocation, paper-feeding mechanism supported by said carriage, a platen carried by said carriage and fixed relatively thereto, means for guiding the paper at its edges and faces over said platen and impression-making mechanism pivotally mounted on said base and operatively positioned relatively to said platen.

45 2. In a typewriter, a frame comprising a base and a carriage bed fixed thereto, a carriage supported on said bed for reciprocation, a paper-feeding mechanism supported by said carriage, a platen carried by said carriage, means for guiding the paper between said bed and said platen and impression-making mechanism pivotally mounted on said base and operatively positioned relatively to said platen.

50 3. In a typewriter, a base plate, a carriage bed, one of said members having a resilient flange, means on said flange for engaging said other member to hold the members together, said means being held in

operative relation by the resilience of said flange.

4. In a typewriter, a frame comprising a base plate and a carriage bed, said base and bed having interlocking parts, and said base being resilient whereby said parts may be sprung into interlocked relation and held in that position by the resilience of the bed.

5. In a typewriter, a frame comprising a base and a carriage bed, said bed comprising a top and resilient supporting pieces, said base and pieces having interlocking parts and being held in interlocked position by the resilience of said pieces.

6. In a typewriter, a base comprising side bars and a cross-bar, a plurality of flanges upon said cross-bar, impression-making mechanism supported by certain of said flanges, an escapement-operating key carried by another of said flanges, flanges on said side bars and a carriage bed connected with said flanges.

7. In a typewriter, a base-plate having a slotted flange, key members pivoted to said base-plate and passing through said slots, a carriage bed having supporting members, said supporting members being secured to said base-plate, impression members supported on said key members and a paper carriage on said bed.

8. In a typewriter, a frame having a slotted flange, key members pivoted on said frame and passing through said slots, a yoke pivoted to said frame and having a slot and passing under said keys, a paper carriage on said frame, escapement mechanism for said carriage and an escapement-mechanism operating key passing through the slot in said yoke, a spring pressing said yoke upwardly and impression-making mechanism on said key members.

9. In a typewriter, a frame comprising a base, a carriage bed comprising a U-shaped member attached thereto, a carriage slideable on said carriage bed, escapement mechanism for said carriage comprising a rack mounted on said carriage and an escapement member mounted on said frame, said carriage bed having a longitudinal slot through which said rack extends to coöperate with said member.

10. In a typewriter, a frame having a flat top provided with two longitudinal slots, a carriage on said top having means coöperating with the edge of one of said slots to guide said carriage, an escapement rack on said carriage and extending through the other slot, means on said carriage extending through one of said slots and coöperating with the underside of said top to hold said carriage down to said top and escapement mechanism on said frame coöperating with said rack.

11. In a typewriter, a frame comprising a base having perforated flanges, a carriage

- bed comprising a top and supporting pieces 65
projections on said supporting pieces, parts
of said carriage bed being resilient, whereby
the supporting pieces may be sprung to
5 permit the insertion of said projections into
said perforations and the projections thereby
held in place, a carriage slideable on said
carriage bed and impression-making mechanism
supported on said frame.
- 10 12. In a typewriter, a frame comprising a
base having perforated flanges, a carriage
bed comprising a top and supporting pieces,
projections on said supporting pieces, said
15 projections being secured in said perfora-
tions, a carriage slideable on said carriage
bed and impression-making mechanism sup-
ported on said frame.
13. In a typewriter, a frame having a flat
top provided with a longitudinal slot, a car-
20 riage slideable on said top, said carriage
comprising a flat base portion having a
flange at each end and a longitudinal flange
extending downwardly, said last-named
25 flange passing through said slot, an escape-
ment rack, a paper-carrying mechanism
mounted on said end flanges and an escape-
ment mechanism on said frame coöperating
with said rack.
14. In a typewriter, a frame having a flat
30 top provided with two longitudinal slots, a
carriage slideable thereon and comprising a
plurality of longitudinal bars and an end
piece at each end, paper-carrying mecha-
35 nism carried by said end pieces, an escape-
ment rack carried by said carriage and ex-
tending through one slot in the top, escape-
ment mechanism on said frame coöperating
40 with said rack, a flange extending from one
of said bars and through the other slot, an
other of said bars forming a platen, and
impression-making mechanism on said
frame.
15. In a typewriter, a frame having a flat
top provided with two longitudinal slots, a
45 carriage slideable thereon and comprising a
plurality of longitudinal bars and an end
piece at each end, paper-carrying mecha-
nism carried by said end pieces, an escape-
50 ment rack carried by said carriage and ex-
tending through one slot in the table, es-
capement mechanism on said frame coöper-
ating with said rack, a flange extending
55 from one of said bars and through the other
slot, another of said bars forming a platen
and having a flange extending from one of
its edges to form a paper guide.
16. In a typewriter, a frame having end
members supporting a flat top, said top com-
60 prising two bars, a carriage slideable on said
top comprising a plurality of longitudinal
bars and an end piece at each end, paper-
holding mechanism, an escapement rack car-
ried by said carriage, a plurality of lugs ex-
tending from the bars on said carriage and
engaging the lower side of the bars of the
frame, the end members of said frame being
slotted to permit the passage of only certain
of said lugs, escapement mechanism and im-
pression-making mechanism supported on
said frame.
17. In a typewriter, a frame having a flat
top provided with a longitudinal slot, a car-
70 riage slideable on said top, said carriage
comprising a flat base portion having a lon-
gitudinal flange extending downwardly, said
flange passing through said slot, an escape-
75 ment rack, a paper-carrying mechanism
mounted on said carriage, and an escape-
ment mechanism on said frame coöperating
with said rack.
18. In a typewriter, a frame having a top
supported by end members, said top having
a slot therein, a paper carriage slideable on
80 said top, means extending from said car-
riage through said slot and engaging the
lower side of said top to hold said carriage
down and to guide it, said end members be-
ing formed to coöperate with said means to
85 limit the movement of the carriage, and im-
pression-making mechanism supported on
said frame.
19. In a typewriter, a frame comprising
end members and top bars, a paper carriage
90 slideable on said bars, means extending from
said carriage and engaging the lower side of
said bars to hold said carriage down and
guide it, said end members being formed to
95 coöperate with said means to limit the
movement of the carriage, and impression-
making mechanism supported on said frame.
20. In a typewriter, a frame comprising
end members and top bars, a paper carriage
100 slideable on said bars, means extending from
said carriage and engaging the lower sides
of said bars to hold said carriage down and
to guide it, said end members being formed
105 to coöperate with certain of said means to
limit the movement of the carriage, and im-
pression-making mechanism supported on
said frame.
21. In a typewriter, a frame comprising a
base and a flat carriage bed, a paper carriage
110 slideable on said bed comprising two bars
and end pieces, means on one of said bars
coöperating with said bed to guide and hold
down said carriage, said other bar comprising
115 a platen and being offset relatively to
said first bar to permit paper to pass be-
tween it and the carriage bed, and impres-
sion-making mechanism on said frame.
22. In a typewriter, a frame having a flat-
topped paper-supporting portion, impres-
120 sion-making mechanism including impres-
sion bars which bars pass through said flat-
topped portion, a carriage mounted on said
frame for reciprocation, a flat platen carried
125 by said carriage against which the paper is
held by said flat-topped portion of the frame,

and mechanism on said carriage for feeding the paper between the top and the platen.

23. In a typewriter, a frame comprising a base and a carriage bed, keys pivoted to 5 said frame, an impression bar pivoted to each key and supported thereby, a carriage mounted for reciprocation on said bed, a paper holding and feeding means on said carriage, a platen fixed to said carriage and 10 over which the paper is fed and means on said bed for guiding said bars and holding the paper against said platen.

24. In a typewriter, a base comprising a substantially flat plate, impression-making 15 mechanism including impression bars mounted thereon and supported entirely thereby, a carriage bed, comprising an inverted U-shaped member mounted on said plate and having means guiding said impression bars 20 for reciprocatory motion, and a carriage slideable on said carriage bed.

25. In a typewriter, a base comprising a substantially flat plate, impression-making 25 mechanism including impression bars mounted thereon and supported entirely thereby, a carriage bed comprising an inverted U-shaped member mounted on said plate and having means guiding said impression bars 30 for reciprocatory motion, and a carriage slideable on said carriage bed and having a

flat platen positioned over said impression bars.

26. In a typewriter, a frame, impression-making mechanism and a carriage mounted thereon, flanges on said frame having perforations, a shaft having perforations therein and passing through said frame having first-named perforations, the end of one of said flanges having an additional perforation, and a pin passing through said last-named perforation and the 35 perforation in the shaft, and a spring connected to and wound around said shaft and attached to said carriage.

27. In a typewriter, a frame including a top and supporting members therefor, portions of said supporting members being bent 40 inwardly under said top, a shaft mounted in said portions and held against rotation, a spring secured to and wound thereon, a carriage mounted on said frame, said spring 45 being attached thereto, and impression-making mechanism mounted on said frame.

In testimony whereof, I have signed my name to this specification, in the presence of two subscribing witnesses.

JAMES J. O'REGAN.
